UNITED STATES PATENT OFFICE.

EVA PHILLIPS, OF MISSOULA, MONTANA.

KITCHEN-CABINET.

1,261,162.

Specification of Letters Patent.

Patented Apr. 2, 1918.

Application filed November 19, 1914. Serial No. 872,983.

To all whom it may concern:

Be it known that I, EVA PHILLIPS, a citizen of the United States, residing at Missoula, in the county of Missoula and State 5 of Montana, have invented certain new and useful Improvements in Kitchen-Cabinets, of which the following is a specification.

This invention relates to kitchen cabinets, and more particularly to a cabinet of this 10 character which can be readily and easily folded or collapsed for storage, moving, or shipping.

The invention consists in the novel features of construction, combination and arrangement of parts as will be hereinafter more fully described, illustrated in the accompanying drawings and claimed.

In the drawings:

Figure 1 is a perspective view of a cabinet 20 net constructed in accordance with the invention.

Fig. 2 is a similar view showing the cabinet folded for shipment.

Fig. 3 is a longitudinal sectional view.

Fig. 4 is a transverse sectional view.

Fig. 5 is a front elevation showing a cabinet folded, and

Fig. 6 is an end elevation showing the cabinet folded.

30 The improved cabinet comprises a base structure, which base structure comprises a baseboard 1, end pieces 2, front and rear side pieces 3, and legs 4 which are hingedly connected to the under face of the baseboard 35 for folding relation therewith, the side pieces 3 having recessed portions 5 formed therein for a purpose which will subsequently appear.

The cabinet proper comprises a rear wall 40 6 which is hingedly connected with the rear piece or base-board 3, of the base structure, as at 7; end walls 8 and 9, which are hingedly connected with the end pieces or boards 2, as at 10 and 11, respectively; and the 45 front wall 12, which is hingedly connected to the front piece or board 3 of the base structure, as at 13; the front and rear walls being normally held in rigid engagement with the end walls by means of screws 14.

50 A top 15 is detachably hinged with the rear wall 6 as at 16, and is provided with sliding leaves 17 which are slidably engaged in brackets 18 upon the underface of the top, and extend through recesses 19 formed in 55 the front wall 12.

Partitions 20 may be provided for the

spacing of the interior of the cabinet into compartments, and these partitions are engaged in recesses formed in the upper face of the baseboard 1 in order to provide for 60 the rigidity of the same.

By reference to the drawings it will be seen that upon removing the pintles of the hinges 16 the top may be readily removed; also, by removing the screws 14 it 65 will be seen that the end walls may be folded down upon the baseboard 1, and the front and rear walls may be folded upon the end walls. The legs may be folded upon the underface of the baseboard, and by inverting 70 the top the collapsed major portion of the cabinet may be placed on said top in order to form a compact bundle, the slides 17 being adapted to rest within the recesses 5 cut in the side walls of the frame structure, while 75 the upturned legs are inclosed between the thus transposed top and the base-board or floor of the cabinet.

If desired, doors 20' may be provided for the front of the cabinet in order to provide 80 access to any of the compartments therein.

From the foregoing description taken in connection with the accompanying drawings, it is thought that the construction and operation of the device will be clearly understood, and while I have herein shown and described one specific form of my invention, I do not wish to be limited thereto, except for such limitations as the claims may import. 90

I claim:

1. A kitchen cabinet, comprising a base board, legs hingedly connected to the base board to fold against the underside thereof, end walls hinged about in line with the top 95 of the base board to fold thereon, side pieces projecting above and below the base board, front and rear walls hinged to the side pieces to fold on the end walls, partitions stepped in recesses in the top of the base board, and 100 a top detachably hinged to the rear wall.

2. A collapsible kitchen cabinet comprising a base structure, said base structure comprising a baseboard, end pieces secured to said base board, side pieces secured to said baseboard, one of said side pieces having recesses therein, front, and rear and end walls hingedly mounted on the respective side and end pieces of the base structure, a top 105 detachably mounted on said rear wall partitions attachable on said baseboard, and extension pieces slidably engaged with the un-

derface of the top and removable therewith, said extension pieces adapted to rest within the said recesses when the cabinet is in a collapsed condition.

5. 3. In a collapsible kitchen-cabinet, the combination of a base-board, side pieces and end pieces affixed to said base-board in such relation as to project to a level below the level of the under surface of said base-board
10 and form an inclosure, said side pieces being cut out on their respective lower edges, side walls hingedly connected to said side pieces, end walls hingedly connected to said end pieces, a cover adapted to be positioned on
15 the upper edges of said side walls and end walls, extensible leaves carried by said cover, and legs connected with and supporting said base, said legs being foldable upward with
20 in said inclosure and against said base-board, said leaves being seated in the cut out portions of said side pieces when the kitchen-cabinet is folded, thereby confining said legs between said base-board and said leaves.

4. A collapsible kitchen-cabinet comprising

ing a floor, legs hingedly mounted to fold 25 up against said floor, side-boards and end-boards secured to the respective sides and ends of the floor and extending above the latter and also extending below the latter sufficiently to inclose the legs when said legs 30 are folded up, side and end wall members mounted on the respective side-boards and end-boards and foldable over said floor in superposed position, a cover removably secured normally on top of said side and end 35 wall members, and an extensible leaf movably secured to said cover and removable therewith and adapted to be inclosed by the lower portion of said boards while said cover is in a transposed position in which 40 the lower edges of said boards rest upon said cover, when said cabinet is collapsed.

In testimony whereof I affix my signature in presence of two witnesses.

EVA PHILLIPS.
